Primary Examiner — Shannon W Morgan

(57) **CLAIM**

The ornamental design for a carousel for holding coffee pods, as shown and described.

DESCRIPTION

FIG. 1 is a top perspective view of a carousel for holding coffee pods showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof; and,
FIG. 7 is a bottom plan view thereof.
The broken lines shown in the figures depict portions of the carousel for holding coffee pods that form no part of the claimed design.**1 Claim, 7 Drawing Sheets**(56)
